UNITED STATES PATENT OFFICE.

JOHN FREDERICK MATTHEWS, OF DOVER, ENGLAND.

CONCRETE BUILDING.

Application filed June 16, 1920. Serial No. 339,429.

To all whom it may concern:

Be it known that I, JOHN FREDERICK MATTHEWS, a subject of the King of Great Britain and Ireland, and residing at 29 5 Heathfield Avenue, Dover, in the county of Kent, England, have invented certain new and useful Improvements in Concrete Buildings, of which the following is a specification.

10 This invention relates to concrete buildings and methods of constructing same, and has for its object to provide means whereby such structures may be rapidly and cheaply constructed from parts which may be more 15 or less standardized while at the same time the structure will be strong and durable and fireproof or practically so.

20 The invention consists in a method of constructing concrete buildings from elements which may be formed separately in any desired situation and afterwards assembled on the site which the building is to occupy.

25 The invention also consists in buildings formed by the above method and other details and arrangements hereinafter described or indicated.

The accompanying drawings illustrate one form of building constructed in accordance with the invention.

30 Figure 1 is a sectional elevation.

Fig. 2 is a plan view of the base member for joists and wall studs, the floor joist only being shown.

35 Fig. 3 is a plan view showing the base member for the reception of floor joists only.

Fig. 4 is a plan view of the base member for reception of a wall stud only.

Fig. 5 is a secondary view of Fig. 2.

Fig. 6 is a secondary view of Fig. 4.

40 Fig. 7 is a front view of Fig. 3.

In carrying my invention into effect in one convenient manner as, for example, in its application to the construction of a dwelling-house, I provide concrete or other foundations *a* under the external and party walls, such foundations being formed in any usual 45 or approved manner.

Upon the outer foundations I arrange a concrete base *b* which is provided with a 50 drip *c* moulded on the underside in order that any moisture collecting thereon may fall clear of the damp course, and in the external face of such member *b* I provide a rebate adapted to receive the outer wall slab 55 or slabs *d* in such a position that such outer

wall will obtain a bearing upon the foundation and preferably flush with the outer face thereof so that the drip only overhangs the foundation.

The outer face of the base member *b* is carried to a sufficient height to preclude the possibility of moisture entering the space between the inner and outer slabs *d* constituting the walls and may be damp-proof in any suitable manner. 60

The base member is formed of reinforced concrete and has apertures formed therein at suitable intervals to receive the wall studs and floor joists *g*, the latter being separately formed of reinforced concrete in any suitable manner and being of a size and shape 65 to correspond with the size and shape of the apertures provided for their reception in the base member *b*, the reinforcements of the studs and joists being left projecting beyond the ends of same so that they may be suitably hooked to or otherwise connected with the reinforcement of the base member, the junctions of such respective members being 70 afterwards grouted to complete the joints. 75

If desired suitable sound-proof material may be placed over the joists prior to laying the concrete floor *h*, the latter being made as one or more slabs of reinforced concrete, the size of such slabs being dependent upon 80 the size of the room or the means available for handling such slabs.

Round the outer edge of the flooring slabs is formed a shallow rabbet or depression in order to take the reinforced concrete skirtings *i* which serve as bearings for the inner wall slabs *e*; the wall slabs or such of them as may be necessary being moulded with 85 holes or apertures for the reception of bolts *k* connecting the slabs or connecting the outer slabs and skirtings or cornices. 90

The reinforced cornices *l* are moulded to form ceilings *m* and picture rails *n* and the reinforcements of the studs are connected with the reinforcement of the cornices, the upper floors *m* being provided with apertures to enable the reinforcements of the 100 upper studs to pass therethrough to the cornices.

Where required for sliding or hanging doors *o*, windows *p* and other like parts appropriately shaped and dimensioned studs will be provided. 105

Reinforced concrete frames complete with sill, mullions and crown and having metal 110

window frames moulded therein are separately formed for assembling in the completed structure, the sills *s* being each provided with rabbets for the reception of the outer and inner wall slabs and being also provided with a drip *t*, a similar drip being furnished in the crown *u* of the window frame.

In all parts of the structure external surfaces may be formed of dense damp-proof concrete while the inner surfaces are formed from a more porous concrete with the object of preventing condensation, and it will be understood that wherever required throughout the structure any suitable damp-proofing and sound-proofing means may be provided.

For the roofing of the structure I form reinforced concrete roof trusses complete with rafters *v*, central upright *v'*, diagonals *v²* and horizontal tie beam *v³* all in one piece, the rafters overhanging the walls to form eaves and being suitably hooked or otherwise formed at the extremities *v⁴* to carry gutters.

Notches are formed in the upper side of the rafters to serve as stops for the roof slabs *w* which are preferably of such dimensions that the ends meet over dividing walls and so that the high roof section will overlap the lower section with the centre of the lap *w'* immediately over the diagonal struts *v²* of the roof truss.

The parts of the roof slabs forming the ridge are arranged so that waterproofing material may be inserted in a slot or opening along the ridge to obviate the use of ridge tiles while the slabs and rafters are provided with necessary bolt holes to permit the securing of the slabs in position, and the lower sides and ends of the roof slabs are arranged with a drip such as *w²*.

If necessary or desirable the floors may be completed by overlaying the concrete slabs with wood blocks or other suitable material.

The doors used throughout the structure may be of sheet metal or formed of other suitable material and may be arranged to slide or to hang, the rollers or other anti-friction fittings for sliding doors being preferably carried at the top, while the hinge fittings if the doors are of the hang-

ing variety are arranged as usual at the sides.

It is to be understood that the foregoing details of construction are given by way of example only as I may variously modify the shape and method of constructing the various elements from which my improved buildings or fences are to be formed depending upon the character of structure that is required, and I may modify also the character of the reinforcement and the method of uniting the various elements of the structure to one another, all as may be determined by any practical requirements that the invention may be called on to fulfil.

Having now described my invention what I claim as new and desire to secure by Letters Patent is:—

1. A reinforced concrete building of the type referred to, comprising a base member adapted to support the outer wall slabs and having apertures formed at suitable intervals therein to support wall studs and floor joists, concrete floor slabs supported upon said joists, skirtings round the outer edges of said floor slabs, inner wall slabs supported on said skirtings, reinforced concrete cornices resting on the wall studs and inner wall slabs, upper floor slabs resting on said cornices substantially as described.

2. A reinforced concrete building as claimed in claim 1 in which the cornices are moulded to form ceilings substantially as described.

3. A reinforced concrete building according to claim 1 in which the cornices are moulded to form ceilings and comprising reinforced concrete roof trusses each formed complete with rafters, central upright, diagonals, and horizontal tie beam and means uniting said horizontal tie beam to said moulded ceiling.

4. In a reinforced concrete building as claimed in claim 1, the base provided with a drip moulded on its under side and having on its external face a rabbet adapted to receive the outer wall slab or slabs substantially as described and for the purpose set forth.

In testimony whereof I have signed my name to this specification.

JOHN FREDERICK MATTHEWS.
